UNITED STATES PATENT OFFICE.

ELMER H. GUTKNECHT, OF MILWAUKEE, WISCONSIN.

PLANE.

1,322,011.

Specification of Letters Patent. Patented Nov. 18, 1919.

Application filed June 27, 1918. Serial No. 242,280.

To all whom it may concern:

Be it known that I, ELMER H. GUTKNECHT, a citizen of the United States, residing at Milwaukee, in the county of Milwaukee and State of Wisconsin, have invented certain new and useful Improvements in Planes, of which the following is a specification.

This invention is a plane and has special reference to a carpenter's plane.

10 One object of this invention is the production of plane, wherein simple and efficient means are provided for adjusting the blade and retaining the same in an adjusted set position.

15 Another object of this invention is the production of a plane wherein a plurality of meshing beveled gears are provided, also means for driving the gears and means for causing one of the gears to engage the blade, whereby the blade may be vertically adjusted.

20 Another object of this invention is the production of a clamping bar, which includes a rack, thus permitting a pinion to engage the rack for urging the bar in either of two directions, whereby when desired, the bar may be brought into a binding engagement with the clamping block of the blade for holding the blade in a vertically adjusted position.

25 Broadly stated, the invention consists of a plane body having a pocket formed therein, a clamping block positioned upon said blade, a pair of beveled gears, carried upon said body and engaging said blade, whereby when the gears are driven, said blade will be vertically adjusted, a clamping bar extending longitudinally of said body and engaging said block and said blade, a pinion carried 30 by said body and engaging said bar for shifting the same, thus causing the bar to hold the same in an adjusted set position or which may be moved for releasing the blade from a clamped position and allowing 35 the gears to adjust the same.

One practical form of construction and assembly of the present invention will be hereinafter described and is illustrated in the accompanying drawings, in which—

40 Figure 1 is a side elevation of the plane.

Fig. 2 is a vertical section taken on the line 2—2 of Fig. 1.

Fig. 3 is a vertical section taken on the line 3—3 of Fig. 1.

45 Fig. 4 is a central longitudinal section through the plane, portions of the body at

the ends thereof being broken away and Fig. 5 is a detail perspective view of the rear portions of the blade.

In the preferred embodiment of the present invention about to be described, it will be seen that the plane body 10 is elongated, and is substantially square in cross section, as shown in Fig. 2, although of course, it is obvious that any form of body desired 60 may be employed. As herein illustrated, the body 10 is provided with a rounded rear end portion 11 while the corners at the front of the body are beveled off as indicated at 12, thus providing a body which will tend 65 to minimize danger of accident by the engaging of the ends thereof with the various articles. The body 10 has handles 46 and 47.

The body 10 is provided with a pocket 13 intermediate its ends, as shown in Fig. 75 4. This pocket 13 has a slanting rear wall 14, this wall 14 being provided with an off-set portion 14'. The side walls 15 are parallel, as shown in Fig. 3, although it will be noted that the front wall 16 slants 80 upwardly and that the pocket 13 is provided with an opening 17 extending to communicate with the bottom of the body 10. This body 10 is also provided with a socket 18 in front of the body 13, and it is noted 85 that this pocket is substantially square and is closed at its bottom, as it only extends for a short distance into the top of the body, as shown in Figs. 2 and 4. It will further be noted that a reduced bore 19 extends 90 longitudinally of the body 10 and communicates at its ends with the socket 18 of the pocket 13, for purposes to be herein-after set forth.

The blade 20 is somewhat similar in construction to the usual blades now in use, in connection with a plane, as will be seen by referring particularly to Fig. 5. This blade 20 is elongated and is beveled at its lower edge to provide a cutting edge 21. 100 The blade 20 is also provided with a longitudinally extending slot 22 formed therein, while a rack 23 is formed upon the rear surface of the blade 20. It is of course obvious that if so desired, instead of forming a rack, as shown in Fig. 3, parallel slots may be provided in the blade without departing from the spirit of the present invention. This blade 20 is inserted into the pocket 13 to allow the cutting edge 21 to 110 extend through the opening 17, although the upper portions of the blade 20 will ex-

tend above the top of the body 10, as illustrated in Figs. 1, 3 and 4.

A standard 24 is carried upon the body 10 at a point in the rear of the pocket 13 and the beveled gear 25 is rotatably supported upon the standard 24. It will be noted that the beveled gear 25 is provided with teeth 26 upon its periphery, as shown in Fig. 4. When the device is in use, the teeth 26 engage the rack 23, formed on the blade 5, for purposes to be hereinafter set forth.

A housing 27 is fixed in any desired manner upon the body 10 and this housing is provided with a journal 28. The shaft 29 is carried by the journal 28 and extends into the housing and carries a beveled gear 30 upon its inner end, which meshes with the beveled gear 25. A grip 31 is carried upon the outer end of the shaft 29.

Therefore, it is obvious the grip 31 may be grasped and rotated, thus imparting rotary motion to the shaft 29. This action causes the gears to be rotated and as the gear 25 rotates, it is obvious it will shift the blade 20 vertically, in view of the engagement between the teeth 26 of the gear 25 and the rack 23 of the blade 20. Thus, the blade may be adjusted with respect to the degree with which it is to extend beyond the lower portion of the plane body 10, for different kinds of work.

The clamping block 32 is elongated and extends into the pocket 13 formed in the plane body 10. This block 32 is provided with an off-set lug 33 which bears upon the blade 20 in alinement with the housing 27, while the lower end of the block also bears upon the blade in alinement with the slanting wall 14 of the pocket 13. This block is provided with a longitudinally extending slot 34 formed therein, as shown in Fig. 4 and it will be noted that the slot 34 is in direct alinement with the slot 22 formed in the blade 20.

The clamping bar is indicated in general at 35 and it will be noted by referring to Fig. 4 that this clamping bar extends longitudinally of the plane body 10. This clamping bar 35 comprises a thickened body 36 having a reduced shank 37 extending from one end thereof, while the neck 38 extends beyond the shank 37. The body 36 is carried within the pocket 13 in the plane body, although it will be seen that the shank 37 extends through the slot 34 formed in the clamping block 32, thus allowing the rear end of the body 36 to bear upon this clamping block. The neck 38 extends through the slot 22 formed in the blade 20 and thus allows the shank 37 to bear upon the blade 20. The rack 39 is formed or carried on the forward end of the body 36 and this rack 39 extends through the bore 19 formed in the plane body 10 and also projects into the socket 18. It will be noted that the rack 39

is guided in its movement by a bearing plate 40 carried by the plane body adjacent the bore 19.

The shaft 41 is rotatably mounted upon the plane body 10, extending transversely thereof, to have one end projecting into the pocket 18, while the opposite end will extend beyond the outer surface of the body 10, as illustrated in Fig. 2. The outer end of the shaft 41 is provided with a milled grip 42, while a pinion 43 is keyed upon the inner end of this shaft. This pinion is in position to mesh with the rack 39, as shown in Figs. 2 and 4. Therefore, when the grip 42 is grasped and the shaft 41 is rotated, rotary motion will be imparted to the pinion 43 and then to the rack 39. Therefore, the clamping bar may be moved in either of two directions for clamping the blade 20 in a set position or for relieving the clamping action for permitting of adjustment of the blade. It will be seen that the outer portions of the socket may be covered by a closure plate 44 retained in position by screws or other retaining means 45.

When this device is in operation, the grip 42 may be actuated for rotating the shaft 41 in a counter-clock-wise direction, thus causing the pinion 43 to move the rack 39, thus moving the clamping bar 35 forwardly. Therefore, the clamping block 32 and the blade 20 will be released from their clamped adjusted position. The grip 31 may then be grasped and the shaft 29 rotated in either of two directions, thus causing the beveled gears 30 and 25 to be rotated, whereupon the teeth 26 will cause the rack 23 to shift the blade 20, either upwardly or downwardly. Therefore, the cutting edge of the blade 21 may be moved to a desired position with respect to the bottom of the plane body 10, for allowing various thicknesses of cuts to be made when the plane is in use, for either making comparatively thick cuts upon the timber or for finishing work, owing to the manner in which the blade is adjusted. After the blade has been moved to an adjusted position, the shaft 41 may be rotated in a clock-wise direction, thus causing the pinion 43 to shift the clamping bar rearwardly and bring the same into a binding engagement with the clamping block 32 and with the blade, for clamping the blade in an adjusted engagement with the rear wall of the body and also with the housing, thus causing the blade to be held against accidental movement when the same is in operation.

After the blade 20 has been adjusted and is finally clamped by the block 32 in position, this block in turn being retained by the clamping bar 35, the operator while gripping the plane body will also hold the grip 31 between the thumb and finger of the right hand while his hand will hold the plane 130

body, while the left hand of the operator may fit over the forward portion of the plane body and the grip 32 may likewise be held by a thumb and finger, thus causing the 5 clamping means to be firmly held in position to hold the blade 20 in an adjusted position.

The foregoing description and the drawings have reference to what may be considered the preferred, or approved, form of 10 my invention. It is to be understood that I may make such changes in construction and arrangement and combination of parts, materials, dimensions, et cetera, as may 15 prove expedient and fall within the scope of the appended claims.

Having thus fully described my invention, what I claim as new and desire to secure by Letters Patent, is:—

20 1. In a device of the class described, the combination of a plane body, a vertically adjustable blade carried by said plane body, a clamping block bearing upon said blade, a clamping bar shiftable longitudinally of 25 said plane body and engaging said block and blade, and a rotatable pinion carried by said plane body and engaging said clamping bar,

for adjusting and holding the same in a set position, whereby said bar will hold said block and blade in a set position as and for 30 the purposes set forth.

2. In a device of the character described, the combination of a plane body, a vertically adjustable blade carried by said plane body, a clamping block bearing upon said blade, 35 said block and blade having aligned longitudinally extending slots, a clamping bar movable longitudinally of said plane body, said bar comprising a thickened body having a reduced shank terminating in a neck, 40 said shank extending into the slot of said block and said neck to the slot of said blade, thus causing the bar to bear upon said block and blade, the forward portion of said block having a rack, and a rotatable pinion carried 45 by said body, and meshing with the rack to shift the bar for holding the block and blade in a set position.

In testimony whereof I affix my signature in presence of two witnesses.

ELMER H. GUTKNECHT.
